(57) **CLAIM**

The ornamental design for a roof vent, as shown and described.

DESCRIPTION

FIG. 1 is a front perspective view of a roof vent according to the present invention.

FIG. 2 is a bottom perspective view of the roof vent illustrated in FIG. 1.

FIG. 3 is a front elevation view of the roof vent illustrated in FIG. 1.

FIG. 4 is a rear elevation view of the roof vent illustrated in FIG. 1.

FIG. 5 is a side view of the roof vent illustrated in FIG. 1.

FIG. 6 is another side elevation view of the roof vent illustrated in FIG. 1.

FIG. 7 is top plan view of the roof vent illustrated in FIG. 1; and,

FIG. 8 is a bottom plan view of the roof vent illustrated in FIG. 1.

The broken lines shown in FIGS. 3-8 are for the purpose of illustrating environmental structure and form no part of the claimed design.

1 Claim, 6 Drawing Sheets
